UNITED STATES PATENT OFFICE.

HERBERT E. WHITE, OF YOUNGSTOWN, OHIO, ASSIGNOR TO THE GENERAL FIRE-PROOFING COMPANY, OF YOUNGSTOWN, OHIO, A CORPORATION OF OHIO.

WIRE-FASTENING DEVICE.

1,136,746.

Specification of Letters Patent.

Patented Apr. 20, 1915.

Application filed February 25, 1914. Serial No. 821,074.

To all whom it may concern:

Be it known that I, HERBERT E. WHITE, a citizen of the United States, residing at Youngstown, in the county of Mahoning and State of Ohio, have invented certain new and useful Improvements in Wire-Fastening Devices, of which the following is a specification.

This invention relates to an improved wire fastening device possessing special utility as a fastening means for securely and rigidly clamping wires to metal posts and all metal structures used for fencing or other purposes.

To this end, the invention contemplates a wire fastener of very simple construction and which can be economically manufactured from stampings, and easily and readily applied without the use of any special tools or appliances. At the same time, the invention provides a device which holds a wire to a post under very strong tension so that slipping or displacement of the wire from normal causes is made impossible. At the same time, the improved fastener is unaffected in its clamping action by temperature changes causing contraction and expansion of the metal parts.

With these and other objects in view which will be readily apparent to those familiar with this class of devices, the invention consists in the novel construction, combination, and arrangement of parts hereinafter more specifically pointed out, illustrated, and claimed.

A preferred embodiment of the invention is shown in the accompanying drawings, in which—

Figure 1 is a side elevation of a fence post illustrating a number of line wires, each of which is clamped thereto by one of the improved fastening devices. Fig. 2 is an enlarged detail view in perspective of a section of the fence post illustrating the first position of one of the fasteners when applied to the wire, and showing the position of its locking shank prior to being wedged through the slot in the post. Fig. 3 is a view similar to Fig. 2 showing the fastener in its locked position with the locking shank thereof engaged within and against the post. Fig. 4 is a cross sectional view on the line 4—4 of Fig. 3. Fig. 5 is a cross sectional view on the line 5—5 of Fig. 3. Fig. 6 is

a detail view in perspective of one of the 55 fastener keys.

Like reference characters designate corresponding parts in the several figures of the drawings.

The improved fastening device primarily 60 consists of what may be termed a fastener key designated in the drawings by the reference letter K and formed from a strip of metal preferably of comparatively thin steel. This strip of metal is provided at one end 65 thereof with a T-shaped fulcrum member T which includes a cross head 2 and a stem portion 3, the latter being bent on a curve to constitute what may be termed a saddle piece which fits over the top and outer side 70 of the line wire w. At the side of the saddle piece or stem portion 3 beyond the cross head 2, the metal strip, constituting the body of the key, is formed into a locking shank 4 having a substantially V-shaped 75 channel in one side thereof to give the shank the form of a wedge with the inclined sides 5 (as plainly seen in Figs. 5 and 6 of the drawings), and at the free or swinging end thereof, the said channeled locking 80 shank is provided with terminal catch projections 6 which are disposed at one side of the shank and projected from the edges of the inclined sides 5 thereof.

Cooperating with each fastener key K is 85 a metal post P. This post is provided with a longitudinal slot 7 in one side thereof through which slot each fastener key is inserted and locked. That is to say, to provide for fastening a wire w upon the outside 90 of the post P, the cross head 2 at one end of the fastener key is slipped through the slot 7 and turned crosswise thereof so as to be disposed inside of the post and in engagement in the wall thereof at the opposite sides 95 of the slot 7. As thus positioned, the saddle piece 3 is engaged over and at the front of the wire P with the locking shank 4 disposed within the vertical or longitudinal plane of the slot 7, as shown in Fig. 2 of 100 the drawings. The distance between the inclined sides 5 of the locking shank, particularly at the catch terminals 6—6 thereof, is greater than the width of the slot 7 so that by forcibly pressing the shank 4 inward 105 through the slot 7, the wedge formation of the shank 4 permits the same to crowd its way into the slot 7 past the opposite edges of

the slot, and when entirely clear from such edges to snap into engagement with the post and behind the inner edge portions of the slot 7, as may be plainly seen from Figs. 3 5 and 5 of the drawings.

In carrying out the invention, the spring action referred to may be provided for solely in the spring of the sides of the post P when the wedge shank 4 is crowded through the 10 slot 7, or in the spring of the metal fastening key, or partly by the spring of both, so it will further be understood that changes in the form, proportion, and minor details of 15 construction may be resorted to without departing from the spirit or sacrificing any of the advantages of the invention.

I claim:

1. A wire fastening device comprising in combination with a post, a fastener key of 20 substantially T-shaped formation consisting of a fulcrum member and a locking shank disposed substantially at right angles to each other, and each adapted to have a locking engagement with the post wholly within the 25 latter.

2. A wire fastening device comprising in combination with the slotted post, a fastener key having at one end a wire engaging T-shaped fulcrum member engaged within the post across the slot thereof, and a wedging 30 locking shank adapted to have a spring-locking engagement behind the edge portions of the slot.

3. A wire fastening device comprising in combination with the longitudinally slotted 35 post, a fastener key having at one end a T-shaped wire engaging fulcrum member engaging within the post across the slot thereof, said key also having a channeled locking shank of wedge form in cross section and 40 provided with terminal catch projections having a spring-locking engagement with the edge portions of the slot.

In testimony whereof I hereunto affix my signature in the presence of two witnesses. 45

HERBERT E. WHITE.
